UNITED STATES PATENT OFFICE.

WILLIAM F. ROTH, OF NEVADA, OHIO.

ROOFING-TOOL.

1,171,067.

Specification of Letters Patent.

Patented Feb. 8, 1916.

Application filed November 7, 1914. Serial No. 870,898.

To all whom it may concern:

Be it known that I, WILLIAM F. ROTH, a citizen of the United States, residing at Nevada, in the county of Wyandot, and State 5 of Ohio, have invented certain new and useful Improvements in Roofing-Tools; and I do hereby declare the following to be a full, clear, and exact description of the invention, such as will enable others skilled in the art 10 to which it appertains to make and use the same.

This invention relates to new and useful improvements in roofing tools, and has for its principal object to provide a simple and 15 efficient tool for forming the standing seams.

Heretofore in the forming of roofing seams it has been the practice for the tinner or person placing the roof in position to use a pair of tongs for first bending over the wider 20 upstanding edge of the tin and then to use a mallet or hammer to bend the same downwardly in position for the finishing and then after the hammering process is completed, to use a pair of tongs to force the joints 25 down tight in order to prevent any leakage.

My invention has for its principal object to eliminate the necessity of the use of more than one tool to complete the entire operation.

With the above and other objects in view, the invention consists in the novel combination and arrangement of parts which will be fully set forth in the following specification and accompanying drawings, in which,

Figure 1 is a front view in elevation of a tool constructed in accordance with this invention, Fig. 2 is a horizontal sectional view illustrating the details of construction, Fig. 3 is an end view illustrating the device in 35 position for the first operation, Fig. 4 is a view similar to Fig. 3 showing the tool after the first operation has been performed and in position for the second operation, Fig. 5 illustrates the second operation of the device, Fig. 6 illustrates the next step following Fig. 5 in the forming of the joint, Fig. 7 is a view similar to Figs. 3 to 6 inclusive, illustrating the device in its finishing position, Fig. 8 is a fragmentary detail perspective view of the angle bending element, Fig. 9 is a detail view of the bearing in which the handle is rotatable, and Fig. 10 is a sectional view of the element illustrated in Fig. 8 showing the same assembled.

Referring now to the drawings by characters of reference, the numerals 1 and 2 designate as entireties the coöperating members

of this tool which are pivoted at 3 in a manner which will be more fully hereinafter described. The member 1 is provided at its upper end with a suitable D handle 4 and at 60 its lower end with the arcuate extension 5. This arcuate extension is provided at its free end with the lateral projection 6 to which the bolts 7, which hold the elements 65 illustrated in Figs. 8 and 10 in operative position, are secured.

These elements which are illustrated in Figs. 8 and 10 form one jaw of the tongs and comprise the substantially triangular body 70 8 having formed at one edge a plurality of cylindrical portions 9 and the element 13. These cylindrical portions are formed with the central longitudinal apertures 10 and are arranged to coöperate with the cylindrical 75 portions 11, having the central longitudinal apertures 12 formed therein, in supporting the coöperating element 13 in position. Each of these elements 8 and 13 is provided with a diagonally extending aperture 14 80 near each end, and a suitable coil spring 15 is secured within the aperture and is arranged to remain under tension so that the elements will be held in the position illustrated in Fig. 10 when in their normal position. A suitable pivot pin 16 is arranged 85 to extend through the apertures 10 and 12 to hold the elements in their proper relation.

The coöperating element comprises the 90 cylindrical handle 17 having formed at its upper end the T gripping portion 18, and the lower end of this handle is reduced as at 19 and rotatably mounted in the body designated generally by the numeral 20. This 95 body 20 comprises the two coöperating elements 21 and 22, which elements coöperate with each other in forming the jaw opposite the jaw hereinbefore referred to. The element 21 is provided with a plurality of 100 screw threaded apertures and has formed integral therewith the downwardly extending portion 23 which terminates in the hook portion 24. This body 21 is provided with the semicircular recess 25 which coöperates 105 with the recess 26 formed in the body portion 22 to form a bearing in which the reduced end 19 of the handle 17 is rotatably mounted. The body 22 hereinbefore referred to is provided with the laterally extending flanges 27 through which the bolts, 110 which extend into the threaded recesses formed in the body 21, project, and these flanges are arranged to coöperate with the

bolts to hold the two separate elements in operative position. Extending rearwardly from the element 22 are the ears 28 which are provided with suitable apertures through which a suitable pivot pin, which pivotally secures the coöperating member 1 thereto, extends.

The hooked ends 24 of the downwardly extending portion 23 are provided with the 10 coöperating clamping element 29 which is provided at its upper end with the angular extension 30 on which the hinged portion 31 is hingedly secured as at 32. This hinged portion has secured to its upper surface the 15 U-shaped plate 33, one of the arms of which is connected to the link 34, the opposite end of which link is pivotally connected by the screw eye 35 to the rotatable handle 17.

The opposite arm of the U-shaped plate is 20 connected to the tension coil spring 36, the opposite end of which is secured to the staple or other suitable support 37 so that the spring is at all times under tension. It will thus be seen that the element 31 will be 25 supported in the position illustrated in Figs. 3, 4, 6 and 7. In order to prevent the element 31 from swinging beyond a predetermined point, suitable stop members 38 are provided at each end of the device, and it 30 will thus be seen that the member 31 will be held in a plane substantially at right angles to the member 29.

From the foregoing it will be apparent that when it is desired to make use of the 35 device, the tin, which has been previously prepared by bending the edges upwardly as indicated at A and B in Fig. 3, is placed in position and the device is positioned as illustrated in said figure so that the element 31 40 engages the deeper bend A. Upon pulling the handle apart it will be apparent that the two coöperating members will swing on their pivot 3, thereby causing the element 31 to engage the extension of the bend A, thus 45 causing the same to assume the position illustrated in Fig. 4. After this operation the T handle 18 is turned which will cause the shaft 17 to rotate within its bearing and thereby cause the link 34, which is 50 pivoted to the U-shaped plate 33, to force the member 31 downwardly in the position illustrated in Fig. 5. In forcing this member 31 downwardly it will be evident that the free end of the bent-over portion A will 55 be forced into the position illustrated in Fig. 5 and be ready for the final clamping action which is accomplished with the same tool. After the tin is in the position illustrated in Fig. 5, the jaws are opened by 60 forcing the handles toward each other and the T handle is still held in its turned position. This will cause the two members 8 and 13 to swing on their pivots so that the

member 8 will pass beneath the free edge of the tin and after having passed that 65 point, will again spring to its normal upward position, and the device is then ready for the final clamping action which is accomplished after the handle has been released so that the member 31 will spring 70 upwardly into its normal position through the action of the spring 36. The handles are then again forced apart which will cause the member 8 to engage the free edge of the tin and force the same firmly against 75 the portion B, thereby causing the joint to assume the position illustrated in Fig. 7, thus completing the same without necessitating the use of more than a single tool and also without moving the tool from its 80 position on the roof.

It will be clearly seen that with the use of a tool of this character the roofing of buildings may be easily and quickly accomplished at a minimum expenditure of time 85 and labor, and a particularly simple and efficient tool is provided which may be easily and cheaply constructed.

While in the foregoing there has been shown and described the preferred embodiment of this invention, it is to be understood that such changes may be made in the combination and arrangement of parts as will fall within the spirit and scope of the invention as defined in the appended 95 claims.

What is claimed is:

1. A roofing tool comprising a pair of tongs, jaws carried by the tongs, one of the handles of one of the jaws being rotatable 100 with relation thereto, bending elements carried by the jaw in which the rotatable handle is mounted means connecting the bending elements with the rotatable handle to cause the elements to bend when the handle 105 is rotated, and a mandrel carried by the coöperating jaw and arranged to form a coöperating bending element.

2. A roofing tool comprising a pair of tongs, jaws carried by the tongs, bending 110 elements carried by one jaw, a rotatable handle in the jaw on which the bending element is mounted, means connecting the bending elements with the rotatable handle, whereby when the handle is rotated the 115 elements are actuated, and a jointed mandrel carried by the other jaw and arranged to form a coöperating bending element over which the material which is being bent is forced by the bending elements.

In testimony whereof I affix my signature in presence of two witnesses.

WILLIAM F. ROTH.
